UNITED STATES PATENT OFFICE.

ANNETTA COLOMBOT, OF MADISON, CONNECTICUT.

FOLDABLE BOX.

1,114,860.

Specification of Letters Patent. Patented Oct. 27, 1914.

Application filed July 21, 1913. Serial No. 780,250.

To all whom it may concern:

Be it known that I, ANNETTA COLOMBOT, citizen of the United States, residing at Madison, in the county of New Haven and State of Connecticut, have invented certain new and useful Improvements in Foldable Boxes, of which the following is a specification.

This invention relates to improvements in foldable boxes or crates, and has for one of its objects to improve the construction and increase the efficiency and utility of devices of this character.

Another object of the invention is to provide a simply constructed device whereby the parts may be quickly arranged in operative position, or collapsed and folded one upon the other for transportation or storage when not in use.

With these and other objects in view the invention consists in certain novel features of construction as hereinafter shown and described and then specifically pointed out in the claims, and in the drawings illustrative 25 of the preferred embodiment of the invention.

Figure 1 is a perspective view of the improved box in closed position viewed from the front. Fig. 2 is a similar view viewed 30 from the rear. Fig. 3 is a side elevation with the parts in folded position. Fig. 4 is a perspective view with the parts in folded position. Fig. 5 is a transverse sectional view with the parts in folded position. Fig. 35 6 is an end elevation with the parts in folded position. Fig. 7 is a perspective view with the parts in open position to illustrate the construction. Figs. 8 and 9 are enlarged details illustrating the construction of the 40 hinges.

Corresponding and like parts are referred to in the following description and indicated in all the views of the drawings by the same reference characters.

The improved device comprises a bottom member 10 having a lower rear portion 11 stationary with the bottom and with a portion 12 of one end likewise rigidly connected to the bottom as represented at 12. The portion 50 11 of the back extends above the bottom 10 a distance equal to the thickness of four of the members, while the portion 12 extends above the bottom a distance equal to the combined thickness of three of the members, 55 as hereafter explained. Hingedly united to the stationary portion 11 is the upper por-

tion 14 of the back of the box, and hingedly united to the stationary extension 12 is the upper portion 17 of one of the end members. The other end member 18 is hingedly united to the bottom 10 as shown. Hingedly united to the bottom 10 at the side edge opposite to the portion 11, is the front formed in three sections 21—22—23 hingedly united edge to edge, as shown. The top 24 of the box is hingedly united to the upper edge of the portion 23 of the front, the various hinges being represented conventionally at 13.

The contiguous edges of the members 14 and 18, 21 and 12, 21 and 18, 23 and 17, 23 and 18, 14 and 17, are provided with eyes 13' to receive holding rods 19, one of the rod being shown in position in Fig. 7. By this means the various members are held in box-like position and in condition to receive the 75 contents.

When arranged in closed form, as shown in Fig. 1, the back 14 is in vertical alignment with the section 11 while the end portion 17 is in vertical alignment with the end portion 12, and the end 18 in vertical position with one edge against the back 14. The front 21—22—23 folds against one end of the sections 12 and 17 and the end of the 85 end 18, while the top 24 folds upon the upper edges of the members 14—17—18.

When the box device is to be collapsed the rods 19 are detached and the end member 18 folded inwardly upon the bottom 10, the top 24 folded upon the portion 23 of the front, and the folded portions 24—23 folded over the portion 21 of the front and spaced therefrom and upon the folded end 18, the relatively narrow portion 22 permitting the 95 parts to be disposed in parallel relations as shown in Fig. 5. The portion 17 of the opposite end is then folded upon the folded portions 23—24, and the portion 14 of the back folded over the end portion 17. By 100 this arrangement the parts are disposed in the form shown in Figs. 3—4—5—6 and in compact order, convenient for shipment or storage.

The ends 17—18 are held in open position 105 by the coaction of the eyes 13' and the rods 19. A suitable fastening device is also employed to secure the cover 24 to the portion 14 of the back, consisting of hinged hasps 15, and staples 15', and a split rod 26, one 110 portion of the rod being passed between the hasps and the member 14 of the back, and

the other portion passed through the staples and over the outer faces of the hasps. The free ends of the rod are apertured to receive a suitable lock, sealing device, or the like, to enable the crate or box to be secured. The parts are simple in construction, can be inexpensively manufactured and of any required size, or of any suitable material. In Fig. 7 the parts are shown in open position 10 to illustrate the construction more fully.

Having thus described the invention, what is claimed as new is:

1. A foldable box comprising a bottom, an end hingedly united to the bottom at one end thereof, another end formed of a lower portion rigidly connected to the bottom at the other end and an upper portion hingedly united to the lower end portion, a back formed of a stationary lower portion connected to the bottom at its rear edge and an upper portion hingedly united to the lower stationary back portion, a front formed of a plurality of portions hingedly united longitudinally to each other and one of the front portions hingedly united to the bottom, and a top hingedly united to the upper front portion, the first-mentioned end being foldable upon the bottom, the top foldable upon the front portion to which it

is hingedly united and foldable together 30 therewith upon the folded end, the upper portion of the last-mentioned end foldable upon the upper folded front portion, and the upper back portion foldable upon the last-mentioned end portion. 35

2. A foldable box comprising a bottom, a lower back portion rigidly connected to the bottom at the rear, an upper back portion hingedly united to the lower back portion, a lower end portion rigidly connected to the 40 bottom at one end, an upper end portion engaging the lower rigid end portion, an end portion engaging the bottom at the end opposite to the rigid end portion, a front formed of a plurality of sections engaging 45 edge to edge, one of the sections being hingedly united to the bottom, a top portion engaging the upper portion of the front, overlapping eyes engaging in the confronting edges of the end portions and the front and both of the rear portions, and pintle rods extending through the eyes. 50

In testimony whereof I affix my signature in presence of two witnesses.

ANNETTA COLOMBOT. [L.S.]
